UNITED STATES PATENT OFFICE.

WALTER N. VANCE, OF CHICAGO HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS.

METAL SHELVING.

Application filed May 13, 1925. Serial No. 29,915.

This invention relates in general to metal shelving, and has more particular reference to the provision of a construction adapted to readily vary the size of compartments in which to hold various articles in compact, assorted arrangement, as more clearly set forth in my co-pending application Serial No. 407,343, filed September 1, 1920.

A principal object of the invention is the provision of a shelf divider arrangement and mounting of improved form and adapted for general use in metal shelving.

Another important object of the invention is the provision of a structure of the character above-noted, consisting of few and simple parts, easily assembled and rearranged, adapted to be economically manufactured, and which will be strong and durable and not require frequent repairs or replacement of the parts.

Numerous other objects and advantages of the invention will be apparent as it is better understood from the following description, which, taken in connection with the accompanying drawings, discloses a preferred embodiment thereof.

Referring to the drawings,

Figure 1 is a front elevation of a portion of a main shelf assemblage in which my present invention is embodied;

Fig. 2 is a section taken substantially on the line 2-2 of Fig. 1;

Fig. 3 is an enlarged section taken substantially on the line 3-3 of Fig. 1;

Fig. 4 is an enlarged section taken substantially on the line 4-4 of Fig. 2; and

Fig. 5 is a partial vertical section taken substantially on the line 5-5 of Fig. 1.

For the purpose of illustrating my invention I have shown on the drawing a main shelf assemblage comprising uprights 11, preferably of tubular form, and if desired connected with front-to-back partition plates 12. These uprights are provided with a plurality of T-slots 13 arranged at frequent intervals in their side faces and adapted to receive shelf supports 14, these shelf supports by reason of the number of the slots

being vertically adjustable as to height. Main shelves 15 are adapted to rest upon the shelf supports as will be readily understood. A tool or other small article-holder of unitary construction is provided and this consists of side sheet metal plates 16 tapering from the bottom upwardly and provided with inturned front flanges 17 and inturned rear flanges 18. The front flanges are turned back upon themselves providing a curl or false wire edge, the extremities 19 of the flanges resting against the flange bodies. 60

A plurality of closely arranged shelves 21 are positioned between the upright plates 16 and each of these consists of a single plate in the present instance having its front-to-back edges bent up into the flanges 22. These flanges are adapted to lie against the inner face of the bodies of the plates 16 and to be bolted in place by bolts 23 or otherwise fastened. At the rear of each shelf the sheet is bent up at 24 to provide an upstanding wall 25 above which the material is bent inwardly and downwardly at 26 to provide a depending flange 27. This flange is recessed at intervals at 28 and beneath each recess the material of the sheet is pressed inwardly in V formation at the bend 24. This forms gussets or braces 29 arranged beneath the recesses 28. These gussets or braces 29 have two important functions, namely, that of reinforcing or stiffening the material of the shelf and also of forming or helping to form an interlocking connection between the shelf and shelf dividers 31 as will be presently described.

Each shelf divider 31 consists of a long strip of material bent back almost upon itself along its center at 32 and having its longitudinal edges bent in to form flanges 33 facing each other and for receiving between them a fastening bolt 34. The flanges 33 are cut away at the rear to accommodate a gusset or V 29 and the height of the divider is such that when thus engaged its upper edge will rest nicely in the recess 32. A row of apertures 35 extend lengthwise of the shelf and near the front and the

bolt 34 is adapted to be disposed through an appropriate one of these recesses to lock the front end of the shelf divider and maintain it in interlocked engagement with the shelf at its rear end. At the front the sheet 5 21 is turned up into a bin front 36 and to this are secured label holders 37 in any preferred fashion.

The shelf may also be secured to the rear 10 upright flanges 18 of the side plates by bolts 38 taking through the shelf parts 25 at the rear and through these flanges, and, thus constructed and formed, a solid unitary structure results. Miniature shelving construction 15 may be used independently or may be positioned in main shelving by suitably arranging the cross-supports to accommodate it. A shelf, having flanges 39, which may be bolted to the uprights, is provided at 20 the top of said miniature construction to give it proper finish and strength when used alone.

It is thought that the invention and many of its attendant advantages will be understood from the foregoing description, and 25 it will be apparent that various changes may be made in the form, construction and arrangement of the parts without departing from the spirit and scope of the invention or sacrificing all of its material advantages, 30 the form hereinbefore described being merely a preferred embodiment thereof.

I claim:

1. Shelving, comprising, a shelf member having an upturned flange at its rear, the 35 upper edge of said flange being bent down and recessed, and a shelf divider disposed upon the shelf in upright position with its rear edge engaged in a said recess, and means for preventing movement of the front end 40 of said divider.

2. Sheet metal shelving, comprising, a shelf member having an up-turned flange at its rear, the upper edge of said flange being bent downwardly and notched at a plurality 45 of points, a plurality of protuberances formed at the intersection of said flange and said shelf member, and a sheet metal divider formed to embrace said protuberances and to simultaneously engage in a said notch in the downwardly bent portion of the flange to secure an end thereof in place.

3. Sheet metal shelving, comprising, a shelf member having an up-turned flange at its rear, the upper edge of said flange being bent downwardly and notched at a plurality 55 of points, a plurality of protuberances formed at the intersection of said flange and said shelf member, and a sheet metal divider formed to embrace one of said protuberances and to simultaneously engage in one of said 60 notches in the downwardly bent portion of the flange to secure an end thereof in place, said sheet metal divider being adapted to receive a bolt adjacent its opposite end and be-

ing held in fixed position by said bolt, said 65 protuberance and said notch.

4. Sheet metal shelving, comprising, shelf supporting means, a shelf member formed for attachment to said supporting means and to provide an upwardly extending flange along an edge thereof, the upper edge of said flange being formed inwardly of the flange and notched at a plurality of points, a protuberance formed in the shelf member beneath each notch in the inwardly 70 extending portion of the flange, a plurality of spaced apertures arranged in said shelf member in a position remote from said flange, and a shelf divider embracing said protuberance and engaging said notches, and 75 a device extending through the apertures in the shelf member and arranged to secure said divider in fixed position.

5. Sheet metal shelving, comprising spaced apart uprights, a vertical tier of spaced 85 apart shelves disposed between said uprights, each shelf comprising a sheet metal member having opposed flanges, each of which is connected to one of said uprights and each of said shelves having upstanding 90 integral front and rear flanges, the rear flange being bent downwardly at its upper portion to provide a depending fold having a plurality of spaced apart notches therein, said upstanding rear flange being fastened to 95 lateral flanges on said uprights and shelf dividers disposed on the upper surfaces of certain of said shelves, each shelf divider having its top portion engaged within a notch in the depending fold of said rear upstanding flange and means for fastening each 100 divider to its shelf portion to maintain it in predetermined position.

6. Sheet metal shelving comprising a main shelf structure which comprises a plurality 105 of spaced uprights each upright having a vertical series of spaced slots formed therein, a plurality of bearer bars disposed in predetermined registering slots, a plurality of main shelf members supported by said 110 bearer bars and providing a vertical tier of main shelves having shelf spaces between adjacent shelves, and a unitary shelf structure engaging said main shelf structure within one of said shelf spaces to provide supplemental shelves for sundry uses, said unitary shelf structure comprising spaced plates extending vertically between adjacent shelves of said main shelf structure, said spaced plates having relatively wide bases and narrow top portions and vertical rear edges, said vertical edges being inturned to provide 120 vertically disposed rear flanges, a plurality of sheet metal shelves arranged between said plates, said shelves having upright side 125 flanges secured to said plates and upright rear flanges similarly secured to said rear vertical flanges to provide a rigid shelf

structure adapted for assembly within said main shelving whereby said engaging shelf structures are mutually strengthened.

7. Sheet metal shelving, comprising a shelf having an upwardly extending notched portion, a shelf divider comprising a metal tube of substantially triangular cross-section and disposed in said shelf and having an

apex portion companion to and engaging said notched portion thereunder to prevent 10 lateral or vertical movement of the divider, and means engaging the base of said divider and said shelf for securing said divider in fixed position in said shelf.

WALTER N. VANCE.
